UNITED STATES PATENT OFFICE.

ALBERT H. STEBBINS, OF LOS ANGELES, CALIFORNIA.

TABLE CONCENTRATOR.

Application filed November 5, 1924. Serial No. 747,903.

To all whom it may concern:

Be it known that I, ALBERT H. STEBBINS, a citizen of the United States, residing at Los Angeles, in the county of Los Angeles and State of California, have invented an Improvement in Table Concentrators, of which the following description, in connection with the accompanying drawings, is a specification, like characters on the drawings 10 representing like parts.

This invention relates to table concentrators, and more particularly to the novel construction of a concentrator deck.

Table concentrators are extensively used 15 to separate ores and other materials in accordance with their differences of specific gravity, and by varying the construction of the deck, and also the vibratory movement imparted to the deck and the strength of 20 the air forced upwardly through the deck surface, these machines may be used to treat various grades of materials, ranging from materials as coarse as an 8 or 10 mesh to materials as fine as a 200 mesh or even finer.

25 In treating the coarser materials a strong air force may be used to lift the lighter particles, and an energetic movement may be imparted to the deck which causes the materials of different specific gravity to separate rapidly. But in treating materials of 30 fine mesh the force of the air employed must be very slight so as not to carry off the fine values as well as the tailings, and a long deck is desirable so that the materials may 35 be subjected to the successive action of a large number of riffles.

The novel deck of the present invention 40 is designed more particularly to treat materials of fine mesh, and is so constructed that a large number of riffles are provided 45 that terminate along a concentrate wall so that the values are gently treated by the riffles over and over again as they travel lengthwise of the deck. This serves gradually to separate the tailings from the very 50 fine values and avoids stirring the values up so that they will be carried off with the tailings.

An important feature of the present invention 55 resides in a double deck construction consisting of a pair of deck surfaces secured side by side, and inclined transversely so that each deck surface slopes upwardly toward the other and is provided with a large number of inclined riffles that direct the concentrates toward a concentrate wall

located at the crest formed by the two deck surfaces. This construction permits two long narrow deck surfaces to be operated by a single supporting frame, and is particularly well adapted for the treatment of fine materials, as the large number of riffles provided serve gently to stratify the fine materials.

Another feature of the invention resides in the construction by which a single concentrate wall is provided extending from the material receiving end of the deck part way along the deck to receive the materials from both deck surfaces during the preliminary treatment of the materials, and is replaced along the remaining portion of the deck by a pair of spaced concentrate walls having a trough between them to receive the concentrates.

Other features of the invention and novel combination of parts in addition to the above will be hereinafter described in connection with the accompanying drawings which illustrate one good practical form thereof.

In the drawings:—

Fig. 1 is a perspective view of a table concentrator provided with a deck constructed in accordance with the present invention.

Fig. 2 is a sectional view of the operating shaft and eccentric operated sheave.

Fig. 3 is a plan view of the deck shown in Fig. 1.

Fig. 4 is a sectional view taken on the line 4—4 of Fig. 3.

Fig. 5 is an end view of Fig. 3 showing the right-hand end of the machine.

Fig. 6 on an enlarged scale is a front view of one of the doors along the concentrate wall; and

Fig. 7 is a vertical sectional view through Fig. 6.

The table concentrator shown in Fig. 1 may be provided with a supporting base of any well known or preferred construction and consists of side frames formed of longitudinally extending rails 10 secured to uprights 11, and the side frames are connected by transversely extending cross braces 12.

Upon the main frame of the table concentrator is mounted the carriage 13 which is supported for back and forth movement. Various means may be provided for movably supporting the carriage upon its frame, and in the construction shown the frame is provided with upwardly extending bearing blocks 14 near the opposite ends of the

frame, and in each of which is mounted a rocking shaft 15 having at each end a downwardly extending arm 16, and each arm 16 is provided with a laterally extending stub 5 shaft 17. The stub shafts 17 are journaled in bearing blocks 18 secured to the under face of the carriage 13, the arrangement being such that the stub shafts 17 swing thru an arc of a circle as the carriage 13 moves 10 back and forth.

Upon the carriage 13 is mounted the double deck of the present invention and various means may be provided for imparting a back and forth movement to this deck 15 to promote travel of the materials lengthwise thereof. One simple but satisfactory form of operating means is shown in the drawing, wherein a cable 19 is provided, one end of which is secured at 20 to the carriage 20 13. This cable passes around a grooved idle sheave 21 mounted upon a shaft 22 carried by the main frame, and the opposite end of this cable is yieldingly secured to the frame by means of a bolt 23 having a 25 coiled spring 24 mounted upon the bolt and confined between a cross beam 12 of the main frame, and an adjustable nut 25 upon the bolt. The arrangement is such that the cable 19 yieldingly urges the carriage and 30 deck mounted thereupon in a right-hand direction.

The means shown for forcing the deck in a left-hand direction and then releasing it to move in a right-hand direction under the 35 action of the spring 24 consists of a cable 26 secured at 27 to the carriage 13 and an intermediate portion of this cable passes around a grooved sheave 28 mounted upon an eccentric 29 upon the eccentric shaft 30, 40 the ends of which shaft are journaled in the bearing blocks 31 secured to the supporting frame. The opposite end of the cable 26 is anchored to the main frame by an adjustable bolt 32. The eccentric 29 is constructed 45 to rotate within a central bore of the sheave 28 and an anti-friction bearing 33 of any preferred construction may be provided between the eccentric and sheave to reduce friction when the former rotates in the latter. The eccentric shaft 30 may be rotated by a pulley 34, whereupon the eccentric sheave will be moved back and forth by its eccentric to tension the cable 26 so that it will pull the deck in a left-hand direction 50 55 and then slack off this cable to permit the deck to move in a right-hand direction under the action of the compressed spring 24.

In accordance with the present invention the double deck consists of a pair of deck 60 surfaces 35 and 36 which are supported side by side by any suitably constructed frame, so that the surfaces are inclined transversely, as shown, and slope upwardly towards each other, the arrangement being such that the 65 two deck surfaces together form a central

crest extending lengthwise of the deck. The deck surfaces 35 and 36 are preferably perforated and air under pressure may be forced into the chamber 37 below the deck by a fan 38 mounted upon the main frame and 70 having its discharge pipe 39 connected to the deck by a flexible conduit 40. The materials to be treated are delivered to the deck by the hopper 41 and the oppositely inclined deck surfaces 35 and 36 preferably extend 75 into the hopper, as best shown in Fig. 4. The rate at which the materials escape from the hopper 41 may be controlled by adjusting the sliding gate 42, which may be secured in the desired position of adjustment by the 80 thumb nuts 43, and the lower end of this gate preferably is approximately V-shaped to conform to the slope of the oppositely inclined deck surfaces 35 and 36.

By constructing the deck of a pair of oppositely inclined deck surfaces, each surface is relatively long and narrow and may be provided with a large number of diagonally disposed riffles 44, which extend from the lower edge of each deck surface towards the concentrate wall 45 provided at the crest formed by the two deck surfaces. The arrangement is such that as the materials travel lengthwise of the deck, due to the progressive movement imparted thereto by the operating means described, the heavier materials or concentrates will travel along the riffles upwardly towards the concentrate wall while the lighter materials or tailings will flow over the riffles, due to the lateral inclination of the deck surfaces towards a tailing trough 46 at each side of the double deck. The concentrate wall 45 mounted near the hopper end of the deck is provided at 90 its opposite sides with the buffer blocks 47; the arrangement is such that as the materials travel along the riffles 44 towards the concentrate wall they will pile up against the buffer blocks 47 so that they will flow laterally over one or more adjacent riffles and 100 then travel along these new riffles for further treatment, thus being subjected again and again to the separating operation of the inclined riffles.

After the materials being treated have 115 traveled some distance along the concentrate wall 45 the values may be sufficiently separated from the tailings to make it desirable to draw off the values or concentrates. The single concentrate wall 45 therefore does not extend the entire length of the deck, but is constructed so that it branches out, as shown, to form the spaced concentrate walls 48 and 49, having the concentrate trough 50 formed between them, and the spaced walls 48 and 49 are provided with openings 51, controlled by slidable gates 52, which may be opened as desired to draw off the concentrates that have accumulated along the concentrate walls, and 125 130

these gates may be secured in the desired position of adjustment by thumb nuts 53. The spaced concentrate walls 48 and 49 are provided with the buffer blocks 47, the same as the wall 45, so that the separating operation may be continued thruout the entire length of the deck. The tailings which find their way into the side troughs 46 travel along these troughs until they escape from

10 the end thereof into the chute 54, while the concentrates that pass thru the openings 51 into the trough 50 travel along this trough and are discharged from the end thereof into the chute 55.

15 The materials delivered by the few inclined riffles at the discharge end of the deck may be directed by funnel-shaped pipes 56 into the concentrate chute 55.

As a result of the deck construction described, a single table concentrator frame may be provided with a pair of long, narrow deck surfaces, each of which may be provided with a large number of inclined riffles 44 by means of which the concentrates are directed towards the concentrate walls so that they will pile up against the buffer blocks 47 and then fall over laterally for retreatment by other riffles, thus repeating this operation again and again as the materials travel lengthwise of the long deck surfaces. As stated, the present deck construction is designed more particularly for the treatment of fine materials, and since it is difficult to separate the very fine values

30 from the concentrates, the repeated treatment just mentioned is necessary in order to completely separate the values from the tailings. As stated, the inclined deck surfaces 45 are preferably provided with apertures which permit air to be forced upwardly thru the materials being treated as this serves to lift the lighter materials and helps to separate the tailings from the values, but a very slight air pressure must be employed

35 to prevent the fine values from being lifted by the air. By providing the sliding gates 52 for the openings 51, each gate may be raised only sufficiently to permit the heavier materials lying close to the deck surface to

40 escape thru the opening and this will exclude the lighter materials, so that they will travel along the deck surface for further treatment.

What is claimed is:

55 1. A double deck for a table concentrator, comprising in combination, a pair of deck surfaces extending side by side and each inclined transversely at the same inclination thruout its length and in a direction so that the surfaces slope upwardly toward their adjacent edges, a concentrate wall common to the two deck surfaces and extending part way along the crest formed by the meeting deck surfaces, a pair of spaced parallel concentrate walls extending along the deck sur-

faces for another portion of the length of the deck and forming a material receiving passage between them, riffles extending in a diagonal direction upon each deck surface and terminating along the concentrate walls, 70 buffer blocks along said walls against which the concentrates pile up, and gates along the spaced concentrate walls for drawing off the concentrates.

2. A double deck for a table concentrator, comprising in combination, a pair of deck surfaces extending side by side and each sloping transversely thruout its length and in a direction so that the surfaces slope upwardly toward their adjacent edges, a concentrate wall common to the two deck surfaces and extending part way along the crest formed by the meeting deck surfaces, a pair of spaced parallel concentrate walls extending along the deck surfaces for another portion of the deck and forming a material receiving passage between them, riffles extending in a diagonal direction upon each deck surface, buffer blocks along said first mentioned wall against which the concentrates pile up, and gates along the spaced concentrate walls for drawing off the concentrates.

3. A double deck for a table concentrator, comprising in combination, a pair of long narrow deck surfaces extending side by side and each sloping transversely thruout its length and in a direction so that the surfaces slope upwardly toward their adjacent edges, a concentrate wall common to the two deck surfaces and extending for a substantial distance along the crest formed by the meeting deck surfaces, a pair of spaced concentrate walls extending a substantial distance along the remaining portion of the deck and forming a material receiving passage between them, riffles extending diagonally over each deck surface, and a trough between the spaced concentrate walls for receiving the concentrates.

4. A double deck for a table concentrator, comprising in combination, a pair of deck surfaces extending side by side and each sloping transversely thruout its length and in a direction so that the surfaces slope upwardly toward their adjacent edges, a concentrate wall common to the two deck surfaces and extending part way along the crest formed by the meeting deck surfaces, a pair of spaced parallel concentrate walls extending along the deck surfaces for another portion of the deck and forming a material receiving passage between them, riffles extending diagonally over the deck surfaces toward the concentrate walls and arranged in substantially parallel relation, and means for drawing off the concentrates at intervals along the spaced concentrate walls.

5. A double deck for a table concentrator, comprising in combination, a pair of deck

surfaces extending side by side and each sloping transversely throughout its length and in a direction so that the surfaces slope upwardly toward their adjacent edges, a concentrate wall common to the two deck surfaces and extending part way along the crest formed by the meeting deck surfaces, a pair of spaced parallel concentrate walls extending along the deck surfaces for another portion of the deck and forming a material receiving passage between them, riffles extending in a diagonal direction over the deck surfaces toward the concentrate walls, and vertically adjustable gates disposed at intervals along the spaced concentrate wall and adapted to open upwardly from the concentrate surface to permit only the concentrates lying close to the concentrate surface to escape.

20 6. A double deck for a table concentrator,

comprising in combination, a pair of deck surfaces extending side by side and each sloping transversely throughout its length and in a direction so that the surfaces slope upwardly toward their adjacent edges, a pair 25 of spaced approximately parallel concentrate walls extending from the discharge end of the deck lengthwise of the deck and forming between them a long narrow trough disposed between the upper edges of the deck surfaces 30 to receive the concentrates, riffles extending in a diagonal direction over the deck surfaces to direct concentrates against the concentrate walls, and means for drawing off the concentrates at spaced intervals along 35 each concentrate wall.

In testimony whereof, I have signed my name to this specification.

ALBERT H. STEBBINS.
